UNITED STATES PATENT OFFICE.

HUGH C. WATSON, OF DENVER, COLORADO.

SURVEYING INSTRUMENT.

1,348,258.

Specification of Letters Patent.

Patented Aug. 3, 1920.

Application filed December 22, 1919. Serial No. 346,470.

To all whom it may concern:

Be it known that I, HUGH C. WATSON, a citizen of the United States, residing at Denver, in the county of Denver and State of Colorado, have invented certain new and useful Improvements in Surveying Instruments, of which the following is a specification, reference being had to the accompanying drawings.

10 This invention relates to certain improvements in surveying instruments, and more particularly of the character of a theodolite, and it is an object of the invention to provide a novel and improved instrument of this general character wherein the magnetic bearing of an objective sighted, together with the vertical angle that the objective shows either above or below a horizontal plane can be determined at the same time 20 and these two angles read while the objective is still in sight.

It is also an object of the invention to provide a novel and improved device of this general character which may be employed with convenience when held in the hand, and which can also, when desired, be supported by a tripod or other support.

Another object of the invention is to provide a novel and improved device of this general character which, when not in use, can be folded or compacted to occupy a minimum of space, together with means whereby the magnetic needle is rendered inoperative when the instrument is folded or compacted.

An additional object of the invention is to provide an instrument of this general character wherein a properly graduated dial is supported for movement with a magnetic needle, and wherein means are provided by which the magnetic declination of the needle is set off so that the dial will give the true bearing of the point or objective sighted when such true bearing is desired.

45 The invention consists in the details of construction and in the combination and arrangement of the several parts of my improved surveying instrument whereby certain important advantages are attained and the device rendered simpler, less expensive and otherwise more convenient and advantageous for use, as will be hereinafter definitely claimed.

The novel features of my invention will 55 hereinafter be definitely claimed.

In order that my invention may be the

better understood, I will now proceed to describe the same with reference to the accompanying drawings, wherein:

Figure 1 is a view in side elevation with a portion broken away, of an instrument constructed in accordance with an embodiment of my invention, and in an adjustment to read an angle below the horizontal;

Fig. 2 is a fragmentary view illustrating the connection between the magnetic needle and the dial;

Fig. 3 is a fragmentary view partly in section and partly in elevation, of the structure shown in Fig. 2;

Fig. 4 is a view partly in top plan and partly in longitudinal section of the instrument as herein embodied;

Fig. 5 is a sectional view taken through the instrument as herein disclosed, with the clinometer in working position, a second position of the clinometer being indicated by dotted lines, the dial coacting with the metallic needle being in elevation, with a portion broken away, and,

Fig. 6 is a fragmentary view in top plan illustrating the fork carried by the rod 14.

As disclosed in the accompanying drawings, A denotes a casing or housing of suitable configuration and dimensions and formed of aluminum, brass, bronze or other non-magnetic material. The top wall 1 of the casing or housing A is provided with a circular recess or pocket 2 closed by the glass plate 3. The glass plate 3 rests upon an annular shoulder 4 carried by and extending inwardly from the wall of the recess or pocket 2, and said glass plate 3 is maintained against displacement by the spring wire 5 or its equivalent.

6 denotes a bearing post extending within the tubular sleeve or support 7 therefor, and which sleeve is capable of movement longitudinally of the post 6 for a purpose to be hereinafter more particularly referred to. The upper or outer end portion of the post 6 coacts with the bearing point 8, preferably of agate, and which bearing point is firmly attached to the lower portion of the bearing 9, preferably of agate, and on which the magnetic needle N revolves. The bearing 9 coacts with the axial center of a disk or dial D having its peripheral portions provided with the conventional degree graduations 10. The disk or dial D moves with the needle N and coacting with the needle N and the disk or dial D is an adjusting member

11, whereby the magnetic declination of the needle N can be set off and the disk or dial D made to give the true bearing of the point or objective sighted when such bearing is desired.

The periphery of the disk or dial D is provided with the degree graduations 12. The graduations 12 are arranged in reverse or negative position with respect to the 10 graduations 10, so that said graduations 12 may be properly read from a prism or mirror P, to be hereinafter referred to.

Extending radially of the recess or pocket 1 of the casing or housing A is a rod 14 supported substantially midway its length for rocking movement, and the inner extremity of the rod 14 is provided with a fork 15 straddling the post 6 below the sleeve or support 7, so that upon depression of the opposite end portion of the rod 14 the needle N and the disk or dial D are held against rotation by contact of the bearing 9 with the glass plate 3. The outer extremity of the rod 14 extends within a groove 16 within the 25 wall of the recess or pocket 1, and is in operative engagement with the inner end portion of a rod 17 slidably disposed through a suitable opening in the portion of the casing or housing A adjacent the recess or pocket 1. When the needle N and disk or dial D are in their working positions, the rod 17 extends beyond the upper or outer face of the casing or housing A a distance sufficient to permit the depression of said 30 rod 17 to effect the requisite raising or elevation of the needle N and the disk or dial D when it is desired to maintain said needle and disk or dial inoperative. The side face of the casing or housing A adjacent the

40 south side of the disk or dial D is straight and flat, and said straight side or face 18 is at right angles to the radial plane occupied by the north index or pointer 19. The face 18 at a point diametrically opposed to the 45 index or pointer 19 is provided with an opening 20, in which extends a tubular bearing 21 carried by the sight box S. The bearing 21 is in swivel connection with the casing or housing A, whereby the box S may 50 be rocked or rotated about the bearing 21, as a pivot. The box S is hollow and preferably oblong with one end open and having mounted in its open or objective end in a conventional manner a lens L. Although 55 not illustrated, it is to be understood that a combination of lenses and their necessary and essential adjusting appliances may be provided in the open or objective end portion of the box S.

60 The opposite end 22 of the box S is closed, and extending within said box S through the closed end 22 thereof is the properly positioned eye piece 23, having arranged therein the lenses 24 to facilitate the taking of 65 the sight.

Stably affixed to the inner side wall of the box S is an inwardly directed bracket 25, serving as a support for the mirror or prism 26 which overlies the bore of the bearing 21 on an angle of 45°. Through the instrumentality of the mirror or prism the 70 graduations 12 of the disk or dial D can be readily read from the eye piece 23, and which reading is facilitated in view of the fact that the graduations 12 are in reverse 75 or negative positions. It is also to be understood that the periphery T overlies the bore of the bearing 23, so that the graduations 12 carried thereby will be exposed through said bore.

B denotes a casing or housing of substantially the same form and plan as the casing or housing A.

The casing or housing B has one face straight and flat, so that when said flat face of the casing or housing B rests upon the top of the sight box S, said casing or housing A and sight box S are in perpendicular relation. The inner marginal portion of the straight face of the casing or housing B is hingedly connected, as at 27 with the inner 85 marginal portion of the top face of the sight box S, whereby the casing or housing B may be swung with respect to the top or open face of the casing or housing A to serve as a closure member therefor. When the casing or housing B is adjusted into closed position with respect to the casing or housing A a marginal portion of said casing or housing B depresses the rod 14, whereby the needle 90 N and disk or dial D are automatically rendered inoperative when the casings or housings A and B are in folded or compacted relation.

28 is a rotary clinometer provided around 105 the peripheral portion of a face thereof, with the degree graduations 29, and also provided on its periphery 30 with the degree graduations 31 arranged in reverse or negative form with respect to the graduations 29. 110 The graduations 29 are read through a window 32 in a face of the casing or housing B, and which window is closed by the transparent member or glass plate 33.

The clinometer 28 is fixed at its axial center to a supporting shaft 34, having its extremities rotatably engaged in the bearings 35 in the opposed faces of the casing or housing B, and said bearings 35 are preferably of agate. The clinometer 28 has a marginal portion weighted, as at 36, whereby the requisite reading is obtained from the clinometer 28 either above or below the horizontal.

The straight or flat face of the casing or 125 housing B at a point in radial alignment with the axial center of the clinometer 28 is provided with a window 36 closed by a glass plate or transparent member 37, and which window 36 registers with a window 130

38 in the top wall of the sight box S when the casing or housing B is in its extended position or in a position perpendicular to the sight box S. The window 38 is closed by the glass plate or transparent member 39.

Supported by the top wall of the sight box S and extending below the window 38 on an angle of substantially 45° is a mirror or prism 40, whereby the graduation 31 may be readily read from the eye piece 23. The mirrors or prisms 26 and 40 are in close proximity so that the magnetic bearing and vertical angle of the objective can be sighted at the same time, and which two angles can be read while the objective is still in sight. This can also be done when the instrument is being held in the hand, although if preferred the instrument may be mounted upon a tripod or other support, and for which reason the bottom face or wall of the casing or housing A is provided with a conventional attachment 41 for coaction with such tripod or support.

The outer side face of the sight box S is provided with a window 42 closed by the glass plate or transparent sheet 43, and which window is for the purpose of admitting light within the sight box S, and which is also true of the window 32, hereinbefore referred to. The plate or sheet 33 and the plate or sheet 43 are each provided with a fine line or mark 44, extending thereacross in such a way that by reading the closest line of the graduations coacting therewith, the correct angle will be indicated.

The mirror or prism 40 is held in applied position through the medium of the bracket 45, properly engaged with the top wall of the sight box S of substantially the same character as the bracket 25 previously mentioned.

The cross hairs 46 are carried by the reticule 47, and which reticule is positioned in the objective end of the sight box S. Although forming no part of my present invention, it is to be understood that the reticule 47 may be so constructed that the cross hairs 46 may be adjusted to the exact center of the line of sight.

From the foregoing description it is thought to be obvious that a surveying instrument constructed in accordance with my invention is particularly well adapted for use by reason of the convenience and facility with which it may be assembled and operated, and it will also be obvious that my invention is susceptible of some change and modification without departing from the

principles and spirit thereof, and for this reason I do not wish to be understood as limiting myself to the precise arrangement and formation of the several parts herein shown in carrying out my invention in practice except as hereinafter claimed.

I claim:

1. In an instrument of the class described, a casing, a compass rotatably mounted therein, a sight box embodying the usual sight lenses, a tubular connection between said sight box and said casing whereby said sight box is rotatably mounted with relation to said casing, said compass embodying a dial arrangement adjacent said tubular connection, means within said sight box whereby the indicia of said compass dial may be read, a casing pivotally connected to said sight box and adapted to be swung to raised and lowered positions, a sight opening in said last named casing, a sight opening formed in said sight box adapted to coact with the sight opening of said last named opening when the casing is in raised position, a clinometer mounted within said last named casing and embodying a dial and means arranged within said sight box whereby the indicia of the dial of said clinometer may be read.

2. In an instrument of the class described, a horizontal casing having a compass mounted therein, a sight box provided with a tubular bearing affording swivel connection with said casing, said sight box being provided with the usual sight lenses, means arranged within said sight box adjacent said tubular bearing whereby the indicia of said compass may be read, a second casing pivotally connected with said sight box and adapted to be swung to horizontal and vertical positions, said second casing when in the horizontal position forming a closure for said first named casing and when in the vertical position disposed upon the upper surface of said sight box, a sight opening formed in said second casing, a sight opening formed in said sight box adapted to coact with the sight opening of said second casing when said second casing is in the vertical position, a clinometer mounted within said second casing and embodying a dial and means arranged within said sight box adjacent the sight opening thereof whereby the indicia of the dial of said clinometer may be read within the sight box.

In testimony whereof I hereunto affix my signature.

HUGH C. WATSON.
